UNITED STATES PATENT OFFICE.

MILTON W. COOKE, OF MOUNT LEBANON, AND OSCAR WILLIAMS, OF PITTSBURGH,
PENNSYLVANIA.

ELECTRIC SWITCHING DEVICE.

Application filed May 23, 1927. Serial No. 193,495.

Our invention relates to improvements in electrically operated track switches, particularly applicable to street railways in which is employed a spring pressed toggle joint 5 and a solenoid and plunger type armature in conjunction therewith; and the advantages of our improvements are; first, to provide an improved holding device for the switch tongue, second, to apply the electro-mechanical force to the holding parts in the most efficient manner; and third; to reduce the number of parts and joints.

We attain these objects by the electro-mechanical structure illustrated in the accompanying drawing in which—

Fig. 1 is a plan view of the entire apparatus including a section of the track switch, ground box without cover, toggle joint and electro magnet with its plunger armature; 20 Fig. 2 is a side elevation of the apparatus; Fig. 3 is a cross-sectional view of a part of Fig. 1 along the line "A"—"A" with a section of a switch throwing iron added;

Fig. 4 is a cross-sectional view of Fig. 1 25 along the line "B"—"B" with the toggle joint in mid-way position. Levers 1 and 2 are pivoted in bearings cast integrally with ground box 3 by pins 1^a, 2^a. These levers are articulated at their inner ends by pin 4 which also carries one end of plunger link 5, the other end of which is articulated with 30 plunger armature 6^a of magnet 6.

Lever 2 is constructed of two parts, 2^b and 2^c, the latter being telescoped into the former. 35 Adjustable collar 2^a is threaded on to member 2^c so as to effect the desired pressure in the toggle joint by means of spring 7.

Link 8 is fixed to switch tongue 9 of track 10 and attached to lever 1 by pin 1^b so as 40 to permit lost motion between the toggle joint and the switch tongue.

In the lid 3^a, is an opening 3^b, through which switch throwing iron 11 can be inserted so as to engage slot 1^c to lever 1. 45 This arrangement is provided for the purpose of manually throwing switch tongue to the desired position.

Magnet 6 is held in a fixed position in the

ground box or casing 3 by means of lugs 3^b and is constructed with two solenoids 12— 50 13, one at each end to operate plunger 6^a to reverse positions as is usually found in electric switch throwing art such as is found in the patent to Cheatham No. 612,702, issued October 18, 1898. As the current is applied 55 to section 12 of the magnet 6, armature 6^a will be pulled into the center cylinder of the magnet and thereby force the toggle joint to a position opposite that shown in the drawing. As the current is applied to section 13, armature 6^a will be pulled to the position shown in the drawing. With these operations the switch tongue 9 is carried 60 from one position to the other as desired.

We are aware that prior to our invention 65 electrically operated track switches with various spring holding devices have been made.

We, therefore, do not claim such a combination broadly; but we claim:

1. In an electrically operated switch 70 throwing device comprising a solenoid and a magnetic plunger connected to a toggle joint employing a common articulation.

2. In an electrically operated switch 75 throwing device comprising a solenoid and a magnetic plunger equipped with a linkage connected to a toggle joint provided with a pair of levers, said plunger linkage and levers having a common articulation.

3. In an electrically operated switch 80 throwing device mounted within an integral ground box comprising a solenoid and a magnetic plunger connected to a toggle joint with a common articulation.

4. In an electrically operated switch 85 throwing device mounted within an integral ground box comprising a solenoid and a magnetic plunger equipped with a linkage connected to a toggle joint provided with a pair of levers, said plunger, link and levers having a common articulation.

5. In combination with a track switch of 90 an electrically operated switch throwing device comprising a solenoid and a magnetic plunger connected to a toggle joint with a 95

common articulation, and linkage means for connecting the track switch to the toggle joint.

6. In an electrically operated switch throwing device mounted within an integral double compartment ground box, comprising a solenoid and a magnetic plunger disposed in one compartment provided with a linkage

connected to a toggle joint disposed in the other compartment, provided with a pair of 10 levers having a common articulation for said plunger linkage and said levers.

In testimony whereof we affix our signatures.

MILTON W. COOKE.
OSCAR WILLIAMS.
